UNITED STATES PATENT OFFICE

2,456,794

CONVERTIBLE FURNITURE UNIT

Ambrose M. Richardson, Chicago, Ill.

Application August 16, 1944, Serial No. 549,674

12 Claims. (Cl. 155—196)

1

This invention relates to a convertible furniture unit, and more particularly to a combination of separable parts adapted to be interconnected in various ways to form different furniture units from the same parts.

One feature of this invention is that it provides an improved furniture unit; another feature of this invention is that the unit may be converted into a number of different styles, types and articles of furniture all made from the same parts, or from a combination of certain of said parts; yet another feature of this invention is that the furniture unit may be readily and easily converted from one type of furniture unit to another type; still another feature of this invention is that attractive and high-quality furniture units of modern style may be built cheaply in quantity production; a further feature of this invention is that it provides furniture which may be particularly easily stored and shipped, and which is particularly convenient in small apartments; and still a further feature of this invention is that the same furniture units can be used for different purposes at different times, in each case being in the preferred form for the particular use. Other features and advantages of this invention will be apparent from the following specification and the drawings, in which:

Figure 1 is a side elevational view of one form of furniture unit embodying my invention; Figure 2 is a back view of the unit shown in Figure 1; Figure 3 is a fragmentary detail view along the line 3—3 of Figure 1; Figure 4 is another fragmentary detail view, in section, along the line 4—4 of Figure 1; Figure 5 is still a further fragmentary detail view, in section, along the line 5—5 of Figure 1; Figure 6 is a view of another furniture unit utilizing principally the same parts as are utilized in the unit shown in Figure 1; Figure 7 is a side elevational view of a furniture unit, in this case a stool, made from parts and comprising another embodiment of my invention; Figure 8 is a different view of the unit shown in Figure 7, along the line 3—3 in such figure; Figure 9 is a side elevational view of another furniture unit, in this case a straight-back chair, incorporating the parts used in making the unit shown in Figures 7 and 8 and certain additional parts; Figure 10 is a side elevational view of another unit of furniture, in this case an easy chair with a reclining back, principally formed from the same units used for the chair shown in Figure 9, the back of this reclining chair being shown in two different angles; and Figure 11 is a perspective view of another unit of furniture embodying my invention, in this case a settee com-

2

prising a plurality of associated units of the kind shown in Figure 9.

The trend in housing is toward smaller and smaller dwelling units, with less floor space in each room and with less storage space. In large dwelling units it is feasible to have four straight-back chairs conveniently at hand for use in the front room if cards are to be played, for example; several different types of easy chairs for reading or lounging; and a settee or couch. Such a large number of furniture units not only involve the expenditure of a considerable amount of money, but cannot be used in the modern small dwelling because of space limitations.

15 I have devised and am here disclosing and claiming a convertible furniture unit or combination of parts enabling different types of furniture units to be easily and quickly assembled, to suit the requirements of the immediate occasion, from 20 the same basic combination of parts, or certain of such parts. That is, I provide what may be termed a "kit" or combination of furniture parts which may be very quickly and easily assembled and disassembled in various combinations. With 25 this kit or combination of parts the user may make a straight-back chair to be used in association with a desk, for example, or a settee, or a couple of easy chairs for the living room of the apartment, as one representative example. If 30 company are coming in to play cards of an evening, several of said units may be quickly and easily converted into comfortable, upholstered straight-back chairs for use around the card table. On the other hand, if an old crony of the 35 man's is coming over to spend the evening in conversation and smoking, let us say, a couple of units may be made into comfortable easy chairs with an associated footstool or footrest if desired. Moreover, the householder may have several ad- 40 ditional units at hand for use in case of large parties, without the need of undue storage space, since in knock-down form the combination of parts may be stored in very small space, as in one corner of a closet. Similarly, in moving, the 45 furniture units may be knocked down and crated or boxed in very convenient form requiring much less time and cost in the moving. Yet all of these advantages, and others which will be apparent from the following description, are attained in 50 extremely attractive furniture units of modern style.

Basically, my furniture unit includes a supporting member, which may be in the form of a rectangle and provided with a wooden frame and 55 an upholstered spring supported member in turn

adapted to provide support for part of the human body; and a plurality of supporting elements adapted to be readily and conveniently connected to and disconnected from the supporting member, these elements being designed to hold the supporting member in desired position relative to the floor. More specifically, a chair unit may be formed of a pair of identical supporting members, one providing the seat of the chair and the other the back; and a first group of supporting elements may be so connected to the seat member as to hold it in desired spaced relation from the floor, acting as legs, while a second set of supporting elements may serve to interconnect the two supporting members in such a way as to keep the back member in proper relation to the seat member. Convenient interconnection of the members and supporting elements is preferably effected by providing connector devices on each of the supporting members adapted to make connection with the supporting elements in various ways.

In one embodiment of my invention illustrated in Figures 1-6, inclusive, the supporting members, identified as a seat member 15 and a back member 16, are provided with rectangular wooden frames and upholstered supporting surfaces, it being understood that these supporting members should provide a surface which provides a comfortable support, with appropriate upholstering and spring support, and at the same time present a pleasing appearance. For convenience in terminology, the surfaces of the supporting members 15 and 16 opposite the surfaces intended to receive and support a human body will be termed the back surfaces of the members.

These members are each provided, on their back surfaces, with four spaced connector devices in the form of threaded sockets, as the sockets 17a, 17b, 17c and 17d of the member 16, or the socket 18a of the member 15 shown in detail in Figures 3 and 4. Where the supporting member is to be used as a seat member, as the member 15 in the chair shown in Figures 1 and 2, rod-like supporting elements in the form of pipes 19a-d are adapted to have one end threaded into the connector device and the other end rest on the floor. Where one of the supporting members is being used as a back member, as the member 16 in the chair shown in Figures 1 and 2, these first types of supporting elements would not be used.

Each of the supporting members 15 and 16 is also provided on its back surface with another set of spaced connector devices, as the devices 20a-d of the member 16, and 21a-d of the member 15. These connector devices are in the form of tapered channels, secured by screws to the frame of the supporting member. Another or second type of supporting element is adapted to be received in these connector devices 20 and 21 to hold the supporting members 15 and 16 in desired relation to each other, as the supporting elements 22a and 22b. As can be readily seen in Figures 1-5, these supporting elements 22 slip tightly into the connector devices 20 on the supporting member 16 and into the connector devices 21 on the supporting member 15, so that the supporting member 16 is held in a desired position, in this case upright, with respect to the seat member 15.

The first supporting elements 19 readily screw into and out of the sockets or connector devices 18; and the supporting elements 22 may be easily slipped into connected relationship with the con-

nector devices 20 and 21 without the use of tools. It will be readily apparent that, for storage or shipping, the supporting members and supporting elements can be disassociated and made into a compact kit or combination. On the other hand, a very satisfactory chair may be quickly and conveniently assembled when desired. The kit contains several connector elements of the second type at different angles, so that other combinations or units of furniture may be readily assembled. For example, the supporting elements 23 (forming an obtuse angle) may be used to interconnect the supporting members 15 and 16 to provide an easy chair with a reclining back, as shown to the right in Figure 6. Also, another supporting member 24 with supporting leg elements 25a-d may be associated with the supporting member 15 to provide a lounging chair of the deck-chair type, appropriate holding means, as the plate 26 and screws or the like 27a and 27b, being provided to hold the supporting members 15 and 24 in desired relationship. It will also be apparent that use of the supporting member 24 with its legs 25 alone provides a stool.

A preferred embodiment of my invention, also adapted to make different furniture units from the same basic combination of parts, is illustrated in Figures 7-11. Figures 7 and 8 show a stool assembled from certain of the preferred parts; Figure 9 shows a straight-back yet comfortable chair for use in eating, at a writing desk, card playing and the like; Figure 10 shows an easy chair; and Figure 11 a settee, all being made from the same basic parts.

Referring first to the stool shown in Figures 7 and 8, the supporting member here identified as 30 again comprises a rectangular wooden frame which may be covered with leatherette or other appropriate material, the upper surface being padded and supported by coil springs to provide a comfortable supporting surface. The bottom of the supporting member, best seen in Figure 8, is provided with four connector devices in the form of tapered channel sections here identified as 31a-d, these being located in the corners of the supporting member 30 and two of the tapered connector devices having their wide ends facing up (speaking with respect to the position of the parts as seen in Figure 8) and two having their wide ends facing down. The supporting elements in this case are tubes or pipes, two of these being identified as 32a and 32b, which may be chromium plated or otherwise finished. Each of these (as is also the case with the other two supporting elements not visible in Figure 7) are bent at an acute angle, but at a somewhat different angle; and each are provided at their upper ends with plates here identified as 32a' and 32b', for example, adapted to be tightly received within the connector devices 31a and 31b, the plates being correspondingly tapered. These plates are connected to the ends of the supporting elements at some angle other than a right angle, as may be best seen in Figure 7, and the plates on the two legs 32a and 32c are at a somewhat different angle with respect to the adjacent portion of the supporting elements than are the plates 32b' and 32c' with respect to the adjacent portions of their supporting elements. When the parts are used merely to provide a stool as illustrated in Figures 7 and 8 this is not of importance, but the difference in angles is of particular importance in the provision of chairs of the kind illustrated in Figures 9 and 10.

Referring now more particularly to Figure 9,

it will be seen that the legs 32a and 32c have been turned around and arranged oppositely in the connector devices, the supporting element 32c now being received in the connector device 31a and vice versa. This results in the bent portion of each of these supporting elements extending backwardly from the supporting member 30, rather than underneath it as was the case in Figure 7. Another supporting member here identified as 40 is provided with connector devices 41a-d corresponding to the devices 31a-d on the member 30; and the kit of parts includes supporting elements similar to those illustrated and more fully described heretofore in connection with the supporting member 30. In this case supporting elements 42b and 42d correspond exactly in shape to the elements 32b and 32d previously described, but they are placed in the opposite connector devices as illustrated—i. e., supporting element 42d is received in the connector device 41b. The two ends of the supporting elements 32c and 42d on the one hand and 32a and 42b on the other hand, are connected by telescoping tubular connecting means, one of these being shown and identified as 43 in Figure 9. While these are shown as a supplementary separate piece, it will be understood that the connector elements could be so arranged as to telescope, screw, or otherwise fasten directly to each other.

Referring now more particularly to Figure 10, it will be seen that the same basic kit of parts may be used to provide an easy chair with the back at an intermediate angle, as shown in solid lines, or at quite a reclining angle, as shown in dotted lines. In this combination the supporting elements or legs 32a and 32c are placed in the connector devices 31a and 31c as illustrated in Figures 7 and 8; but the supporting elements 32d and 32b are interchanged, the element 32d now being received in the connector device 31b, as illustrated. If connection is now made between the supporting elements 42b and 32d on the one hand, and 42d and 32b on the other hand, the resulting furniture unit will be as shown in solid lines in Figure 10. On the other hand, the supporting elements 42b and 42d may be replaced by the elements 42a and 42c to provide an easy chair with the back at a considerable angle as shown in dotted lines in Figure 10.

It will be immediately apparent that the same basic combination of parts may be used to make a stool as shown in Figures 7 and 8, a straight chair as shown in Figure 9, and either of two types of easy chairs as shown in Figure 10. Moreover, the conversion between different units may be accomplished easily and quickly, and the parts may be knocked down to very small space for storage or shipment. Moreover, a plurality of such "chair" units may be assembled to provide a settee, as illustrated in Figure 11. Here the chair unit comprising the supporting members 30 and 40 is associated with two other chair units comprising the supporting members 50 and 51 and 60 and 61, the three chair units being preferably latched together by appropriate holding means as the plates and screws or the like shown in Figure 6. The result is the provision of a kit or combination of furniture parts comprising supporting members and supporting elements which may be interconnected in various ways to provide different furniture units, and wherein the interconnections are so made that one unit may be quickly and easily converted into a different type of unit.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. A convertible furniture unit, comprising: a supporting member having a rigid base portion having two sides; connector devices attached along the two sides of the base portion and formed with channels tapering divergently outwardly toward the respective sides; a plurality of legs each having a bend intermediate of its length forming two angularly positioned sections; a plate fixed at the upper end of one of said sections of each leg and positioned at an acute angle thereto in a plane normal to the direction of the extent of the channels, said plates being insertible into and removable from said connector devices whereby said legs may be attached to the base portion at different angular positions with respect thereto; a second supporting member similar to the first mentioned supporting member; and a pair of angular legs removably secured to one side of the second supporting member, and means for securing the free ends of the last mentioned legs to the free ends of two of the first mentioned legs to provide a back rest to the furniture unit.
2. A convertible furniture unit, comprising: a first supporting member having a rigid base portion with a plurality of corners; a connector device attached adjacent each corner of the base portion; a plurality of supporting elements each intermediately bent at an acute angle and each having at one end a plate adapted to be inserted into and removed from any of the connector devices; a second supporting member similar to the first supporting member and having two similar angular supporting elements; and means for connecting the free ends of the supporting elements of the second supporting member to the free ends of two of the supporting elements of the first supporting member.
3. A convertible furniture unit, comprising: a first supporting member having a rigid base portion having two sides; connector devices attached along the two sides of the base portion and formed with channels tapering divergently outwardly toward the respective sides; a plurality of angular supporting elements each having at its upper end a plate adapted to be inserted into and removed from any of the connector devices; a second supporting member similar to the first supporting member and having two similar angular supporting elements; and means for connecting the free ends of the supporting elements of the second supporting member to the free ends of two of the supporting elements of the first supporting member, some of said plates being positioned at one acute angle to the adjacent portion of the supporting element in a plane normal to the direction of the extent of the channels and others of said plates being positioned at a different acute angle to the adjacent portion of the supporting element in a plane normal to the direction of the extent of the channels, whereby by a selection of supporting elements the second supporting member may be positioned at different angles to the first supporting member.
4. A convertible furniture unit, comprising: a supporting member having a rigid base portion

having two sides; connector devices attached along the two sides of said base portion and formed with channels tapering divergently outwardly toward the respective sides; a plurality of supporting elements each having an angular bend intermediate of its length and having fixed at one end a plate adapted to be inserted into and removed from any of the connector devices, some of said plates being positioned at one acute angle to the adjacent portion of the supporting element in a plane normal to the direction of the extent of the channels and the others of the plates being positioned at a different acute angle to the adjacent portion of the supporting element in a plane normal to the direction of the extent of the channels, whereby the supporting elements may be attached to the supporting member with the angular free ends pointing inwardly or outwardly of the supporting member as desired.

5. A convertible furniture unit, comprising: a pair of supporting members each having a rigid base portion having two sides; a plurality of connector devices attached along the two sides of each of said base portions; a plurality of supporting elements for each of said supporting members, each supporting element having an acute angle bend intermediate of its length forming two angularly positioned sections one of which sections of each supporting element has fixed thereto a plate adapted to be inserted into and removed from a connector device; one of said supporting members having a pair of supporting elements attached thereto with the free ends of the sections remote from the plates extending laterally outwardly therefrom; and means for connecting said free ends of the last mentioned supporting elements with the free ends of a pair of supporting elements of the other supporting member.

6. A convertible furniture unit, comprising: a supporting member having a rigid base portion having two sides; a plurality of connector devices secured to the base portion along the two sides thereof and formed with channels tapering divergently outwardly toward the respective sides; and a plurality of supporting elements detachably connected to said connector devices, each of said supporting elements having a bend intermediate of its length to form two angularly positioned sections; and plates for attaching the supporting elements to the connector devices, said plates each being positioned at an acute angle to the adjacent portion of its supporting element in a plane normal to the direction of the extent of the channels so that the free end sections of the supporting elements may be positioned underneath the base portion as well as extend laterally outward therefrom selectively as desired.

7. A convertible furniture unit, comprising: a supporting member having a rigid base portion with two opposite sides; a plurality of connector devices secured to the base portion along the two sides thereof and formed with channels tapering divergently outwardly toward the respective sides; a plurality of supporting elements removably connected to said connector devices by plates each fixed to one end of each of said supporting elements at an acute angle to the adjacent portion of its supporting element in a plane normal to the direction of the extent of the channels, the angle of some of said plates with relation to their supporting elements being different from the angle of the other of said

5 plates with relation to their supporting elements, whereby the angle of the supporting elements with relation to the base portion can be varied by changing the position of the plates in the various connector devices.

8. A convertible furniture unit of the character described adapted to provide any desired one of various different furniture units, including: a pair of supporting members; connector devices on each of said members; first supporting elements adapted to have a portion of each rest on the floor and another portion of each removably connected to one of said members by the devices thereon, said elements comprising rod-like elements formed in an acute angle; and second similar supporting elements removably connected to the other member by the devices thereon; two of the first supporting elements and the second supporting elements each having an angular free end extending out from under one edge of its supporting member; and means for detachably connecting said angular free ends together.

9. A furniture unit adapted to provide different furniture articles, comprising: a pair of supporting members one forming a seat portion and the other a back rest, each of said supporting members having a rigid base portion with two sides; connector devices attached along the two sides of each of said base portions and each connector formed with a tapering channel; supporting legs for said seat portion two of which are each formed with an acute angle bend intermediate of its length forming two angularly positioned upper and lower sections, the top end 30 of each of said upper sections having fixed thereto a tapered plate adapted to be removably inserted into a connector of the seat portion, with the bend resting on the floor and the other of each of said sections having a free end extending angularly outwardly from underneath the seat portion; a pair of supporting elements similar in construction to said bent legs and having their end plates removably inserted into a pair of connectors of the back rest; and connecting means 35 for connecting together the angular free ends of the bent legs of the seat portion to the angular free ends of said supporting elements of the back rest.

10. A furniture unit comprising, a supporting member having a rigid base portion with two sides, connector devices attached along the two sides of the base portion, a plurality of legs each having an acute angle bend intermediate of its length forming an upper and lower section, a plate fixed at the upper end of each of said upper sections adapted to be detachably inserted in one of said connector devices, the bend of each of said legs resting on the floor and said lower sections extending angularly upwardly and forming an acute angle with the plane of the base portion.

11. A furniture unit, comprising, a supporting member having a rigid base portion having two sides, connector devices attached along the two sides of said base portion, a plurality of rod-like legs each having an acute angle bend intermediate of its length and forming a knee-portion adapted to rest on the floor and an upper and lower section, each of said upper sections having on its upper end a plate adapted to be detachably connected with one of said connector devices, and each of said lower sections forming an upwardly extending acute angle with the floor when the knee-portion rests thereon.

12. A furniture unit as claimed in claim 11,

in which the number of legs is four, two of said legs having its angularly extending free end pointing inwardly and the other two pointing outwardly of the area of the base portion, a back rest having similar connector devices, plates and a pair of legs similar in construction to said first mentioned legs, said back rest legs having their angularly extending free end portions pointing outwardly of the area of the back rest base portion, and connecting means for connecting said 10 outwardly extending free ends of the legs together.
